DIRECT CURRENT REINSERTING CIRCUIT

Karl R. Wendt, Audubon, N. J., assignor to Radio Corporation of America, a corporation of Delaware

Application October 23, 1940, Serial No. 362,311

8 Claims. (Cl. 178—7.3)

My invention relates to the reinsertion of direct current and/or low frequency components of electrical signals, and particularly to the reinsertion of such components in a television system.

Various circuits have been proposed for the reinsertion of the above-mentioned components where the components have been suppressed during transmission, as, for example, where they are suppressed by transformers or by alternating current amplifiers. These circuits depend for their operation upon the transmission of periodically recurring electrical pulses which are caused to go to a fixed voltage level, such as "black," in a picture, or a few volts beyond "black" before the said components have been suppressed. In television systems, these recurring pulses usually are the synchronizing pulses. A D. C. reinsertion circuit of this character is described and claimed in application Serial No. 658,894, filed February 28, 1933, in the name of Ralph S. Holmes, entitled "Television systems," and assigned to the Radio Corporation of America.

Among the various proposed circuits are the so-called "keyed" circuits of the general type described in Brown, et al., Patent No. 2,190,753, issued February 20, 1940, and in application Serial No. 276,082, filed May 27, 1939, in the name of Henry R. Rhea, both assigned to the Radio Corporation of America. In the circuits as described in these two cases, there is included a triode which is made conducting periodically (that is, it is "keyed") by means of synchronizing pulses or the like to change the charge on a condenser in the grid circuit of the vacuum tube which is to have the reinserted D. C. in its output.

It is an object of my invention to provide improved direct current and/or low frequency component reinserting apparatus and, especially, to provide improved reinserting apparatus of the "keyed" type.

A further object of my invention is to provide an improved D. C. reinserting circuit which is both simple in design and effective in operation.

In practicing the invention, the charge of a condenser in the grid circuit of a vacuum tube is controlled by means of one or more diodes which are keyed by periodically recurring pulses, such as synchronizing pulses. In one embodiment of the invention, there is a single diode which is automatically biased at a voltage sufficient to prevent the condenser from discharging through the diode between successive synchronizing

5 pulses. Upon the occurrence of a synchronizing pulse, the diode is rendered conducting and the condenser will discharge therethrough a certain amount if its charge should be reduced to provide the correct D. C. reinsertion, or it will charge a certain amount through the grid-cathode portion of the tube following the condenser if its charge should be increased. In this case, the control pulses are of positive polarity at the grid 10 of the said tube, and the reference level is the cathode voltage.

15 In the above-described embodiment, the automatic bias which is applied to the diode may be obtained by a D. C. reinserting circuit whereby the D. C. and low frequency components are inserted at the diode. By thus reinserting the D. C. and low frequency components at the keyed diode, any difficulty due to a varying portion of the signal feeding from the keying circuit into 20 the picture signal amplifier channel is avoided. If the picture signal channel received picture signal from the keying circuit which did not contain the D. C. and low-frequency components, there obviously would be an error in the output signal, the error depending upon how much signal fed through the keying circuit.

25 In another embodiment of the invention, two diodes are provided in order that the desired reinsertion may be obtained when the synchronizing or other control pulses are of negative polarity at the point of D. C. reinsertion, that is, at the grid of the tube following the condenser. In this circuit, also, a diode is biased automatically to prevent the condenser from discharging 30 between successive control pulses. The reference level in this case is determined by a bias applied to the other diode.

35 The invention will be better understood from the following description taken in connection with the accompanying drawings in which

40 Figure 1 is a circuit diagram showing one embodiment of my invention applied to television apparatus.

45 Figure 2 is a group of curves that are referred to in explaining the operation of the circuit shown in Fig. 1.

50 Figure 3 is a circuit diagram of another embodiment of my invention, and

55 Figure 4 illustrates a modification of the circuit shown in Fig. 3.

Referring to Fig. 1, the invention is shown applied to a television system in which there is produced a composite signal consisting of picture signals, periodically recurring line synchronizing pulses and periodically recurring

framing pulses. As previously described, the peaks of the synchronizing pulses have been made to go to a fixed voltage level such as a fixed number of volts beyond "black" in the picture before the direct current and low frequency have been suppressed. This may be accomplished in various ways, as by varying the clipping level of a vacuum tube in the way described in Patent No. 2,192,121, issued February 27, 1940, in the name of Alda V. Bedford, or by utilizing a suitable mask with a scanning disc so that the signal goes to "black" at the end of each scanning line.

In Fig. 1, there is shown a conventional alternating current amplifier 10 which has the composite signal applied thereto with such polarity that it appears in the output circuit with the synchronizing pulses of positive polarity as indicated at 11. The pulses 11 are line synchronizing pulses set on a "black" level or pedestal indicated at 12. Picture signal is shown at 13.

It is desired to reinsert at the control grid of the next amplifier tube 16 any direct current and/or low frequency components that have been lost by transmission of the signal through the preceding portion of the signal channel.

Stated differently, it is desired to have the tube 16 supply an output signal in which the peaks of the synchronizing pulses all go to a fixed voltage level. If this is done, correction is made for signal components that have been lost (i. e., they are reinserted) and correction is also made for undesirable effects which may have been introduced, such, for example, as 60-cycle hum.

The amplifier tubes 10 and 16, which may be conventional tetrodes or pentodes, are coupled by a coupling condenser C which, as will be explained hereinafter, has a suitable capacity value to permit, first, the necessary initial charging and, later, the necessary additional charging or discharging in cooperation with the complete circuit for the desired reinsertion of lost components.

In place of the usual grid leak resistor for the tube 16, there is a diode 21 having a cathode 22 connected through a resistor 23 to the control grid 14, and having a plate 24 connected to ground through a resistor 26.

In operation, the positive pulses 11 produce a flow of grid current in the tube 16 which charges the condenser C. It will be seen that, since the cathode of the diode 21 is connected to the negative side of the condenser C, it is connected in the proper direction to discharge condenser C and will do so unless a suitable opposing bias is provided. Such a bias is maintained across the resistor 26 by the action of the positive synchronizing pulses or keying pulses which are applied to the plate of diode 21, these pulses being taken from the output of the tube 16 in the specific example illustrated and applied to the diode plate through an amplifier 31 and a coupling condenser C1.

It may be noted that the keying signal applied to the diode to be keyed should have a peak to peak voltage at least as great as the peak to peak voltage of the signal applied to the amplifier tube 16, and, preferably, should be substantially greater. This is true, also, of the circuit of Fig. 3 which is described in detail hereinafter.

The positive pulses fed through condenser C1 cause a flow of current through the diode 21, the resistor 23, and the grid-cathode impedance of amplifier tube 16. Between successive pulses, the condenser C1 discharges a slight amount through

a path that may be traced through the plate resistor 30 of amplifier 31 to ground, through ground and the resistor 26 back to condenser C1. This current flow through resistor 26 holds the diode plate 24 negative with respect to ground during the time of the picture signal 13, i. e., between succeeding pulses 11, whereby the diode is non-conducting and the charge on condenser C remains unchanged during the transmission of the picture signal itself.

The above-described charging of condenser C1 through the diode and partial discharging through resistor 26 functions to reinsert the D. C. and low frequency components at the diode plate 24 whereby any signal that is fed back through the keying circuit and into the picture signal channel does not vary with picture D. C. content and thus partially spoil the effectiveness of the D. C. insertion in the said signal channel.

The charge on condenser C determines the negative bias on the grid 14 of amplifier 16, this being another way of saying that it determines the amount of D. C. insertion. Variations in this negative bias result in the desired reinsertion of low frequency components and in the removal of hum effects or the like.

During the intervals of transmission of picture signal 13, the bias voltage on the control grid 14 is the voltage across condenser C minus the D. C. voltage on the plate of tube 10. During these intervals, the circuit 23, 21, 26, which corresponds to the usual grid leak, is open-circuited as previously stated. Therefore, the bias on grid 14 cannot be determined by figuring IR drop through a grid leak resistor as is commonly done in the case of a grid-leak biased tube.

The operation of the circuit will now be considered more in detail. First, it should be noted that, just as in the Holmes' invention previously referred to, the basis of the circuit operation is the fact that the height of a synchronizing pulse as measured from the A. C. axis of the composite signal is a measure of the amount of D. C. or low frequency component to be reinserted. Therefore, it is desired to have the present circuit so operate that the charge on condenser C increases if the height of the line synchronizing pulses increases, and that the charge on condenser C decreases if the height of the line synchronizing pulses decreases.

Next, let us assume that the apparatus is in operation and let us consider what happens upon the occurrence of a synchronizing pulse. This pulse is applied with positive polarity both to the grid 14 of tube 16 and to the diode plate 24. Condenser C is charged a slight additional amount through the grid-cathode impedance of tube 16, as previously described, if the pulse is of sufficient amplitude with respect to the A. C. axis of the signal.

Also, condenser C1 is charged through the diode 21 and through the grid-cathode impedance of tube 16. At the end of this pulse, condenser C1 is partially discharging through resistor 26 to hold the diode plate negative, whereby condenser C cannot discharge during the picture signal interval.

Meanwhile, the charge on condenser C holds the grid 14 of tube 16 properly biased and no undesirable saw-tooth components are introduced as may be the case with circuits in which the condenser C may discharge a slight amount during the picture signal interval.

It is essential that the circuit operate to decrease the charge of condenser C in the event

that the recurring pulses decrease in amplitude with respect to the signal A. C. axis. The operation is as follows: Upon the occurrence of a synchronizing pulse of less amplitude than a preceding pulse, the condenser C will not be charged any further because its voltage is greater than the applied voltage. On the other hand, condenser C will discharge enough to bring the condenser voltage to a value of the applied voltage.

This discharge path for condenser C may be traced through the plate resistor 8 of amplifier 10 to ground, through the plate resistor 30 of amplifier 31, the condenser C1 and the diode 21 and resistor 23 to the other side of condenser C. All resistors in this discharge path have such low resistance that the condenser C may discharge sufficiently in a given time to permit the condenser voltage (and, therefore, the voltage on grid 14) to follow the variations in height of the synchronizing pulses.

That the condenser C is discharged to the proper voltage level will be seen considering the discharge path of the condenser C as follows: At the beginning of the synchronizing pulse of reduced amplitude, the signal voltage across the plate resistor 8 is of less amplitude than the voltage across condenser C, the condenser voltage having been determined by the preceding synchronizing pulse. It is desired to discharge the condenser C to a point where its voltage is equal to the signal voltage now appearing across output resistor 8. Obviously, this may be accomplished by connecting the grid side of the condenser C to the ground end of the plate resistor 8. In effect, this is done when the pulse through condenser C1 makes the diode 21 conducting, since the impedance of diode 21 and the impedances of resistors 23 and 30 and condenser C1 are comparatively low. The condenser C1 has a fairly large capacity, usually at least ten times the capacity of the condenser C.

The capacity of condenser C1 is so large that any discharge current from the condenser C can change the voltage across condenser C1 only a negligible amount. As to the D. C. voltage between the diode plate and the ground end of plate resistor 8, the D. C. voltage from the cathode of amplifier 31 to the plate of the diode is zero, since the D. C. charge on condenser C1 is equal and opposite to the voltage applied from the plate battery of the amplifier 31.

The operation of the D. C. inserter may be described from a different viewpoint as follows: First, it should be noted that the positive pulse on the plate of diode 21 which is causing current flow through diode 21 and through the grid-cathode impedance of tube 16, is holding the plate of diode 21 close to ground potential, the diode and grid-cathode impedances being low and the resistance of resistor 23 being low. More particularly, the grid side of condenser C has been driven substantially to ground potential by the pulse through condenser C1. Since the plate side of condenser C is held at a potential determined by the signal, i. e., determined by the height of the synchronizing pulse from the A. C. axis, it follows that the voltage across C is brought to the proper value either by charging or by discharging the condenser C slightly.

The curves in Fig. 2 illustrate, in general, the operation of the circuit. The characteristic curve for the amplifier tube 16 is indicated at 34, while the composite signal which is applied to the control grid of this tube is indicated at 11, 12, 13. 75

It will be seen that the synchronizing pulses 11 produce the charging current for the condenser C by driving the grid of tube 16 into the positive region whereby the resulting voltage across condenser C produces the correct biasing voltage to hold the A. C. axis of the composite signal the proper distance away from zero grid volts, as indicated. It will be noted that between successive pulses 11, the picture signal 13 is amplified by the amplifier 16 operating as a linear amplifier. No attempt has been made to illustrate in Fig. 2 the portion of the cycle of operation involving discharging of the condenser C.

From the foregoing, it will be evident that the charge on the condenser C, and therefore the bias on the control grid 14, is set at the proper value, since the positive pulse fed through condenser C1 drives the grid side of condenser C substantially to ground whereby condenser C may either acquire some additional charge through the grid-cathode impedance of tube 16 or lose some of its charge through the diode 21.

When the circuit connections are as shown in Fig. 1, the resistor 23 generally is included in the circuit to prevent oscillations resulting from the feedback connection through the keying circuit. When the keying pulses are supplied from a feed-forward connection, as when the switch 15 is closed and the switch 20 opened, the resistor 23 is preferably removed from the circuit, in effect, by closing a short-circuiting switch 25.

The resistor 23 may be omitted also in the case where the keying pulses are supplied over a line 35 from a separate source which supplies keying pulses occurring in synchronism with the synchronizing pulses. Keying pulses may be so supplied by connecting the switch arm 20 to the line 35, the switch 15 remaining open.

Instead of feeding both the picture signal 40 and the synchronizing pulses through the keying circuit of Fig. 1, it may be preferable to include clipping tubes in the keying circuit whereby synchronizing pulses only of positive polarity are applied to the diode plate 24. In this case, there is a negative bias voltage applied to the diode plate 24, but the voltage does not represent the picture D. C. component. Since the clipped synchronizing pulses are of constant amplitude, they do not introduce a variation in the signal at the input of amplifier 16 when added thereto and the lack of D. C. component on the diode plate is unimportant.

It has been found that the circuit has less tendency to oscillate due to the feedback of keying signal if the above-mentioned clipping tubes are employed to prevent picture signal from appearing on the diode plate 24.

Referring to Fig. 3, there is shown an embodiment of the invention in which synchronizing pulses of negative polarity rather than positive polarity are applied to the control grid of the amplifier tube 16. In Figs. 1 and 3, like parts are indicated by the same reference characters. The principle of operation of the two circuits is the same, there being two main differences. One difference is that in Fig. 3 there is an additional diode 36 through which the condenser C may receive a charge, this diode being necessary since the pulses are of the wrong polarity to cause grid current flow in the tube 16. Another difference is that, in Fig. 3, the voltage level is not ground potential but, instead, is a certain bias or level setting voltage which is obtained as a result of current flow through the diodes.

A discharge path for the condenser C is pro-

vided by a diode 37 which has its plate connected to the cathode of the diode 36, both of these electrodes being connected through a resistor 38 to the grid side of condenser C. The resistor 38 is not essential to the circuit operation and, for many applications of the invention, it may be omitted, or it may be short-circuited by means of a switch 39. When included in a circuit, the resistor 38 functions primarily to prevent circuit oscillations which otherwise might occur because of the feedback connection through the amplifier tube 46.

The cathode of the diode 37 and the plate of the diode 36 are connected together through a resistor 41. The plate of diode 36 is connected to ground through a condenser 42. The resistor 41 is provided with a variable tap through which any desired point on the resistor 41 may be connected to ground through a resistor 43.

Keying pulses are applied from the output of amplifier 16 through clipping circuits 46 and 47 and through a coupling condenser 48 to the junction point of the resistor 41 and the cathode of diode 37.

These keying pulses are for the purpose of making the diode 37 conducting during the occurrence of synchronizing pulses whereby the condenser C may discharge some if its voltage should be reduced, and also for the purpose of producing a fixed voltage which may be employed for the voltage level setting.

The voltage pulses which are applied to the cathode of diode 37 are referred to as keying pulses and are of negative polarity and of fixed amplitude, these pulses being indicated at 51. The pulses 51 of fixed amplitude are obtained by removing the picture signal in the clipping circuits 46 and 47 whereby the amplitude of the resulting pulses is fixed by the vacuum tube characteristics and by the associated circuit elements.

The clipping tube 46 may be of the well-known type operating on grid leak biasing, as described in Patent 2,132,655, issued October 11, 1938, to J. P. Smith. The next clipping circuit 47 is also of the grid leak biased type and may be omitted if sufficient clipping is obtained in the first clipping circuit. However, the second clipping circuit usually is desirable and, in the example illustrated, it is a circuit of the cathode-follower type which does not reverse the signal polarity and which, therefore, has negative polarity pulses appearing across the cathode resistor 52.

Considering the operation of the circuit of Fig. 3 more in detail, upon the occurrence of a negative keying pulse 51, the diodes 37 and 36 are made conducting whereby the grid side of condenser C is connected through the resistor 38 and the diode 36 to the plate end of resistor 41, this point on resistor 41 being at a predetermined level setting voltage, such as minus four volts. Therefore, if the synchronizing pulse applied through amplifier 10 is of greater amplitude with respect to the signal A. C. axis than was the preceding synchronizing pulse, the condenser receives a slight additional charge through the diode 36.

This charge path may be traced from the lower end of the plate resistor 8 of the amplifier 10, through ground, and through the parallel circuit comprising condenser 42 shunted across resistor 43 and the right portion of resistor 41 to the plate of diode 36, and through the diode 36, the resistor 38 and the condenser C to the plate end of the plate resistor 8.

The condenser C quickly receives a charge since the condenser 42 has low A. C. impedance. Also, the condenser can charge up only to the D. C. voltage which has been selected as a level setting value.

In the event that the next synchronizing pulse supplied from amplifier 10 is of less amplitude than the preceding pulse the condenser C will discharge slightly, the discharge path being from the grid side of the condenser C through the resistor 38, the diode 37 and through the comparatively low impedance elements 48 and 52 to ground, and through ground and the plate resistor 8 back to the plate side of condenser C. It will be apparent that the condenser C cannot discharge below the level setting value because if it should start to do so it would instantly begin to receive a charge through the diode 36 as previously described. This is also apparent from the fact that, when the diodes 36 and 37 are conducting, the cathode of the diode 37 is at substantially the same potential as the plate of the diode 36, that is, it is at the level setting voltage.

Between successive synchronizing pulses, that is, during the picture signal interval, the diode 37 is being held in non-conducting condition by a D. C. voltage across resistor 41, this voltage holding the cathode of diode 37 positive with respect to ground. The signal on grid 14 holds the cathode of diode 36 positive with respect to its plate 4, just as in Fig. 1, it prevents grid current in tube 16 by holding its grid negative. As previously explained, this D. C. voltage across resistor 41 appears as a result of the condenser 42 and 48 (which previously were charged through diodes 36 and 37) discharging through resistor 41, the discharge path being from the condenser 48 through resistor 41 and the condenser 42 to ground, and through ground and the cathode resistor 52 and back to the condenser 48. Thus, it will be seen that, just as in the circuit of Fig. 1, the condenser C cannot discharge during the interval between successive synchronizing pulses.

In Figs. 1 and 3 the values of certain circuit elements have been indicated in ohms, megohms, microfarads and micro-microfarads. These values are given merely for the purpose of illustration and may be varied within wide limits.

In Fig. 3, just as in Fig. 1, the keying pulses 50 may be obtained from a point other than one following the D. C. insertion. For example, the keying pulses may be fed over a line 60 and through the switch 61 to the diodes 36 and 37, the pulses being obtained from any suitable source of pulses which are synchronized with the line synchronizing pulses.

It may also be mentioned that the circuit of Fig. 3 will operate for the case where positive pulses are applied to the control grid of tube 16 60 providing the connections of diodes 36 and 37 are reversed, and also providing the keying pulses are fed through the condenser 48 with positive polarity instead of with negative polarity.

As illustrated in Fig. 4, the level setting voltage for the circuit of Fig. 3 may be obtained by means of a biasing battery indicated at 65 instead of by means of the resistor 43 and condenser 42 which, in Fig. 3, utilized the flow of diode current for biasing. The circuit of Fig. 3 70 is the preferred circuit since it is usually desirable to avoid the use of batteries which eventually must be replaced by new ones.

The level setting illustrated in Fig. 3 is claimed broadly in my copending application Serial No. 367,323, filed Nov. 27, 1940, entitled "Direct cur-

rent reinserting circuit," and assigned to the Radio Corporation of America.

From the foregoing, it will be apparent that various other modifications may be made in my invention without departing from the spirit and scope thereof.

I claim as my invention:

1. In combination, a source of composite signal consisting of the principal intelligence conveying signals and of control pulses each recurring at intervals, said pulses having an amplitude at least as great as said principal signals of like polarity, the combination of an amplifier tube having a control grid and a cathode, a condenser connected in series with said source and the control grid of said tube whereby said composite signal may charge said condenser, and a discharging circuit for said condenser which comprises a diode so connected that said condenser may discharge therethrough when the diode is conducting, means for so biasing said diode that said condenser cannot discharge therethrough during the intervals of said principal signal, and keying means for making said diode conducting between said last intervals.

2. The invention according to claim 1 wherein said control pulses are applied with positive polarity to said control grid whereby said condenser is charged through said grid-cathode impedance.

3. The invention according to claim 1 wherein a second diode is connected in series with said condenser and the source of said composite signal, and connected in the direction to supply a charging current to said condenser when control pulses of negative polarity are applied to said control grid.

4. The invention according to claim 1 wherein said keying means includes means for applying to said diode a signal consisting of voltage pulses of substantially constant amplitude and containing no picture signal.

5. In a circuit for direct current reinsertion and low frequency correction, terminals across which there appears a composite signal consisting of picture signals and control pulses each recurring at regular intervals, said pulses having an amplitude at least as great as picture signals of like polarity, the combination of an amplifier tube having a control grid and a cathode, a condenser connected in series with the grid-cathode impedance of said tube, means for impressing said composite signal across said series circuit and for charging said condenser, and a discharging circuit which comprises a diode so connected that said condenser may discharge therethrough when the diode is conducting, and keying means for making said diode conducting be-

tween said picture signal intervals and non-conducting during said picture signal intervals, said keying means also comprising means for reinserting the direct current component of said composite signal.

6. In a circuit for direct current and low frequency correction of a composite signal consisting of picture signals and control pulses each recurring at regular intervals said pulses having an amplitude at least as great as picture signals of like polarity, the combination of an amplifier tube having a control grid and a cathode, a coupling condenser connected to said control grid, means for feeding said composite signal through said coupling condenser to said control grid, and a charging and discharging circuit for said condenser which comprises a pair of diodes so connected that said condenser may charge through one of said diodes and discharge through the other of said diodes when said diodes are made conducting, means for so biasing said diodes that said condenser cannot discharge therethrough during picture signal intervals, and keying means for making said diodes conducting between said picture signal intervals.

7. In a circuit for correction of a composite signal consisting of picture signals and control pulses each recurring at regular intervals said pulses having an amplitude at least as great as picture signals of like polarity, the combination of an amplifier tube having a control grid and a cathode, a coupling condenser connected to said control grid, means for feeding said composite signal through said coupling condenser to said control grid, and a charging and discharging circuit for said condenser which comprises a pair of diodes each having a plate and a cathode, the plate of one diode and the cathode of the other diode being connected to said control grid, the other plate and cathode of said diodes being connected to each other through a resistor, means for holding one end of said resistor substantially at ground potential for alternating currents, means for applying keying pulses to the other end of said resistor for making said diodes conducting between said picture signal intervals, and means for maintaining said one end of the resistor at a fixed D. C. potential with respect to ground and for holding the diodes non-conducting during the picture signal intervals.

8. The invention according to claim 7 wherein said last means comprises a condenser connected between said one end of the resistor and ground and further comprising a second resistor connected between ground and a point on the first resistor.

KARL R. WENDT.
